UNITED STATES PATENT OFFICE.

CHARLES HADDAD, OF LONG ISLAND CITY, NEW YORK, ASSIGNOR OF ONE-HALF TO
JOHN FOLCZ, OF NEW YORK, N. Y.

TOY.

1,118,001.

Specification of Letters Patent. Patented Nov. 24, 1914.

Application filed April 21, 1914. Serial No. 833,856.

To all whom it may concern:

Be it known that I, CHARLES HADDAD, a citizen of the United States, residing at Long Island City, county of Queens, and State of New York, have invented certain new and useful Improvements in Toys, of which the following is a specification.

My invention relates to improvements in toys, the object of the invention being to provide a toy representing a pair of acrobats performing upon parallel bars, said figures caused to move a considerable length of time by the action of a spring after the initial movement is imparted to the toy.

15 A further object is to provide a toy of the character stated which is of extremely simple construction, cheap to manufacture, and strong and durable in use.

With these and other objects in view, the invention consists in certain novel features of construction, and combinations and arrangements of parts, as will be more fully hereinafter described and pointed out in the claims.

25 In the accompanying drawings: Figure 1 is a perspective view, illustrating my improved toy. Fig. 2 is a view in vertical section taken transversely through the center of the toy, showing the figure at one end of 30 the toy partly broken away, and Fig. 3 is a view in horizontal section on the line 3—3 of Fig. 2.

1 represents a base, and 2, 2, are vertical posts secured rigidly to the base, preferably by a mortise and tenon connection as shown clearly in Fig. 2. The upper ends of the post 2 are rigidly secured to a horizontal bar 3, and the posts 2 and bar 3 constitute a rigid frame A, which supports a movable 40 frame B normally parallel therewith.

The movable frame B consists of a horizontal bar 4, normally parallel with bar 3, and to which bar 4, vertical bars 5 are secured, and the latter are connected at their 45 lower ends by a horizontal bar 6.

Transverse bars 8 connect bars 5 with posts 2 near their lower ends, and as a connecting medium between these bars 8 and the bars 5, and post 2, I preferably provide 50 screws 9, but it is to be understood that this connection is not a rigid one, but a movable one, so that the frame B is permitted to move up and down. The bars 8 are connected by a longitudinal bar 7, forming a rigid connection between them, and it will

be noted by reference to the drawings that all of the joints of the respective parts, where a rigid connection is desired, are formed by mortise and tenon, while the ends of bars 8 are secured by screws and abut 60 against the faces of the parts to which they are connected.

11 represents a bow spring which is secured at one end to the base, and at its free end projects through a slot 12 in the lower bar 6 of movable frame B, so that the spring serves to elastically support the movable frame and cause the latter to move upwardly and downwardly for a considerable length of time after the initial movement is imparted thereto.

The bars 3 extend out beyond the post 2 and bars 5, and at their free ends are connected by flexible devices 13. These flexible devices may comprise cords or wires, and 75 they have parallel runs from bar to bar spaced apart and located at an angle relative to the vertical axis of the toy.

The two runs 13 of the flexible devices extend through openings 14 in the arms 15 of 80 figures 16. These arms 14 are maintained apart by spacing rods 17, so that the figures will assume the normal attitude. The figures 16 have their arms 15 and legs 18 pivotally connected with the body portions of the figures, so that these arms and legs move and give to the figures a great many different 85 positions which they will assume as they perform their acrobatic stunts by reason of the movement of the flexible devices due to 90 the movement of frame B.

In operation, it is simply necessary to press the movable frame downwardly, and then release the same. The spring 11 will cause the frame B to ride upwardly and 95 downwardly for a considerable length of time, and also cause the frame B to fulcrum as it moves upwardly and downwardly. This movement of the frame B will cause the flexible devices 13 to move and will compel 100 the figures to assume many different attitudes, giving the general appearance of acrobats upon parallel bars. This movement of the figures is due to the varying positions of the flexible devices. When the frame is in the uppermost position, the flexible devices are crossed, but as soon as the spring is depressed, the movement of the movable frame will cause the upper member 105 of the movable frame to move away from 110

the fixed frame and compel the cords to assume a parallel relation and thereby actuate the figures.

While in Fig. 3 the screws 9 appear to 5 tightly bind the parts together, it is to be understood that these screws are relatively small, and that they will not be screwed tightly, but a sufficient play will be allowed to give the necessary movement to the frame 10 B, allowing the latter to move upwardly and downwardly by the action of spring 11. The initial movement may be imparted by touching any part of the frame B or pressing downwardly the projecting end of spring 11, 15 which extends over the base a considerable distance, and may be regarded as a finger rest for starting the operation of the toy.

Various slight changes might be made in 20 the general form and arrangement of parts described without departing from my invention, and hence I do not limit myself to the precise details set forth, but consider myself at liberty to make such changes and

alterations as fairly fall within the spirit and scope of the appended claim.

25

Having thus described my invention, what I claim as new and desire to secure by Letters Patent is:

A toy comprising a base, an upwardly projecting frame rigid with the base, horizontal bars connected to said frame near its lower end, a movable frame mounted to fulcrum against the ends of the horizontal bars, flexible devices connecting the frames, figures supported on and movable by the flexible devices, and a spring secured to the base and connected to the movable frame, substantially as described.

In testimony whereof I have signed my name to this specification in the presence of 40 two subscribing witnesses.

CHARLES HADDAD.
